UNITED STATES PATENT OFFICE

SOL M. BRENNER, OF BALTIMORE, MARYLAND, ASSIGNOR TO M. S. LEVY & SONS, INC.,
OF BALTIMORE, MARYLAND, A CORPORATION OF MARYLAND

HATBAND ASSEMBLY

Application filed August 6, 1929. Serial No. 383,914.

This invention relates to improvements in hat band assemblies, and more particularly to an easily locatable and removable hat band.

It has heretofore been proposed to employ easily locatable and removable hat band assemblies, especially with hats of the stiffer type, such as straw hats. According to the present invention, the hat band is maintained under tension while located upon the hat by the provision of an elastic member for supporting and connecting the final attaching hooks to the hat band proper.

An illustrative form of application of the invention is shown in the accompanying drawing, in which:

Figure 1 is a perspective view showing the parts in a semi-applied position.

Fig. 2 is a view on a larger scale, showing the band assembly from the inner side.

Fig. 3 is a corresponding sectional view on line 3—3 of Fig. 2.

Fig. 4 is a perspective view of a hook which may be employed in the assembly.

According to the present invention, a straw hat having the brim 10 and crown 11 is to be provided with a hat band which is included in a finished assembly ready for application to the hat. It will be understood that the hat bands are woven of a strong, substantially inelastic fabric. These bands are liable to slide up and down on the side wall of the crown while in service, leading to the possible loosening of the band from the hat.

The hat band 12 proper is provided at one end with attaching hooks 13 which are formed with prongs adapted to bite into the straw of the hat and thus secure this end against displacement when traction is exerted along the line of the band. At the other end of the band it is provided with a loop member 14 and an enclosing loop 15 forming a bow for the hat. In the particular embodiment selected for illustration in Fig. 3, the hat band 12 is rebent at its end to form the loop member 14, and brought back and laid flat against this end of the band, with a small refold 16 which is secured by stitches 17 to the band itself. The so-called bow is completed by the enclosing loop 15 which is usually formed with

an overlap 18 along the center of its length for the sake of appearance, and has its ends joined by stitches 19 at the reverse side (Fig. 2). To stiffen the bow thus formed it is customary to provide a piece of cardboard or similar material 20 which is stitched to the band 12 itself. 55

According to the present invention, the end 21 of an elastic member is likewise secured to the end of the hat band as by sewing to the card 20, and has a loop 22 at the end in extension of the band proper. A metal plate 23 having the backwardly bent hooks 24 thereon and provided with eyes 25 is then sewed to the elastic member so that the stitches 27 pass through the eyes 25 and thus the metal plate is secured intermediate the length of the elastic member and removed from the stitches 26 which secure the end 21 of the elastic member to the card 20. The hooks 24 are forced through the elastic material and project relatively inwardly when the hat band assembly is located upon a hat. 65

To locate the assembly upon a hat, the hooks 13 at the end of the hat band are engaged in the hat material, and by traction upon the band 12 in the direction of its length the hooks are drawn down into the hat. It is preferred to give this traction to the hat band by pulling with the thumb and forefinger upon the loop 22 of the elastic member in the manner shown in Fig. 1, since in this way there is no soiling or danger of tearing of any part of the hat band proper. 75 As the hat band is wound around the hat, this tension is maintained and by reason of the securing of the metal plate 23 and its hooks 24 at a distance from the stitches 26, the elastic member is maintained under tension. 80 When the band has been brought to completely surround the hat, the hooked ends 24 are forced down into the fabric of the hat band 12 and/or into the side wall of the hat crown according to the size of the hat and the length 85 of the hat band, and upon releasing the pulling tab formed by the loop 22, the elasticity of the member maintains the hat band under uniform tension, regardless of any slight change in the shape or length of the band 90 95 100

by reason of change in the band itself or the hat upon which it is located.

It will particularly be noted that no tension is exerted upon the bow proper, and that the folded end 14 of the bow serves to 5 hide and conceal the pulling tab 22 while the hat is in service.

It is obvious that the invention is not limited solely to the form of execution shown, 10 but that it may be varied in many ways within the scope of the appended claims.

What I claim as new and desire to secure by Letters Patent is:

1. In a hat band assembly, a hat band adapted to surround a hat, and having means at 15 one end to secure it to the hat, an elastic member secured at one of its ends to the other end of the hat band and forming an extension of the hat band, a securing hook attached to said elastic member intermediate 20 the length of said member, and a member secured to said band and overlapping the elastic member and hook to conceal the same normally, said elastic member serving as a tag by which the member and hat band may be 25 placed under initial tension in locating the hat band around the hat and serving after said hook is engaged to maintain said hat band under tension.
2. In a hat band assembly, a hat band 30 adapted to surround a hat, and having means at one end to secure it to the hat, an elastic member secured at one of its ends to the other end of the hat band and forming an extension of the hat band, a securing hook attached 35 to said elastic member intermediate the length of said member, said elastic member serving as a tab by which the member and hat band may be placed under initial tension in locating the hat band around the hat and serving after said hook is engaged to maintain 40 said hat band under tension.

In testimony whereof, I affix my signature.
SOL M. BRENNER.
